Attest:

Glenn L. Tracy

UNITED STATES PATENT OFFICE.

HENRY C. MILLER, OF MILWAUKEE, WISCONSIN.

LOOSE-LEAF BINDER.

1,247,704.

Specification of Letters Patent. Patented Nov. 27, 1917.

Application filed April 11, 1916. Serial No. 90,304.

To all whom it may concern:

Be it known that I, HENRY C. MILLER, a citizen of the United States, and resident of Milwaukee, in the county of Milwaukee and State of Wisconsin, have invented certain new and useful Improvements in Loose-Leaf Binders; and I do hereby declare that the following is a full, clear, and exact description thereof.

10 The present invention relates to new and useful improvements in loose leaf binders and is more particularly directed to the provision of means for detachably securing the binder posts to the binder heads whereby the 15 posts may be detached for the insertion or removal of leaves.

It is primarily the object of the present invention to provide a holding bar arrangement for the detachable binder posts which 20 is in its operative movements disposed wholly within the binder head, and with which is associated suitable key controlled means whereby it may be actuated.

It is also an object to provide such an arrangement wherein a key member upon its 25 proper insertion in the said means adapts the bar to be moved and whereby turning of the key member procures operative movement of the bar to thus provide a ready and 30 quick means for manipulating said bar.

It is further an object to provide a means for locking the bar against releasing operation irrespective of the said key controlled 35 means whereby the binder may be adapted to form a permanent record.

With the above and other objects and advantages in view, the invention resides more particularly in the novel combination, arrangement and formation of parts more 40 particularly hereinafter described and particularly pointed out in the appended claims.

In the drawings:

Figure 1 is a longitudinal sectional view through a loose leaf binder head constructed in accordance with the present invention, 45 this view being as indicated by the line 1-1 of Fig. 3.

Fig. 2 is a similar sectional view taken on a plane disposed inwardly of the plane 50 of Fig. 1, and indicated by the line 2-2 of Fig. 3.

Fig. 3 is a transverse sectional view through the improved loose leaf binder, this section being cut through the key-controlled 55 pinion of one binder head, and through a

post engaging bolt portion of the other binder head.

Fig. 4 is a fragmentary plan view of the outer face of one of the binder heads, showing the key tumbler.

Referring now more particularly to the accompanying drawings, each of the binder heads therein shown is similar in nature to provide for the detachment of the posts from either head, and each comprises a body plate 5 having one side edge portion bent laterally and inwardly at 6 to form a channel in which is slidably mounted the bolt bar 7, the outer portions of the free extremities of this side edge portion being further bent 70 inwardly at 8 to close the channel and thus provide a means for positively guiding the bolt bar, and this closed channel end structure is strengthened by tongues 9 struck inwardly from the body plate thereagainst. 75 The outer side of the channel is cut away at spaced intervals to provide sockets 10 for receiving the apertured ends of the flexible binder posts 11; the bolt bar 7 adjacent these openings is cut away at 12, and bolt 80 sections 13 extend across these cut away portions from corresponding ends thereof, and are adapted to engage through the apertures of the binder posts when disposed in said recesses 10 to thus secure the binder 85 posts, these bolt sections being of different lengths whereby they may successively move into the recess upon actuation of the bar 7 to facilitate the connection of the binder posts therewith inasmuch as the partially projected end of one bolt section will hold the respective binder post, while the other binder post is being positioned in its recess.

The key controlled means for actuating the bolt bar 7 comprises a tumbler block 14 riveted or otherwise secured as at 15 to the inner face of the body plate 5 and having a portion projecting into a cut away portion 16 in the turned edge portion 6 of the plate. A tumbler 17 is rotatably mounted 100 in this block and has its portion adjacent the bolt bar 7 peripherally toothed to provide a gear pinion 18 and this gear pinion meshes with a rack series of gear teeth 19 formed in the bar. The tumbler is provided 105 with a key receiving recess 20 which at the face portion of the tumbler is substantially zig-zag to correspond with the cross-section of a suitable key member 22 and thus upon insertion of the key member in the tumbler 110

it may be readily turned and thus slide the bar to secure or detach the binder posts from the head.

- To provide means for locking the bar
- 5 against movement except when the key is properly inserted in the tumbler, the block is provided with a bore 23 extending transversely from the tumbler and slidable in this bore is a plunger 24, urged by a spring
- 10 25 in the outer portion of the bore to engage in an alining bore 26 formed in the tumbler. Also disposed in the bore 26 of the tumbler is a ball 27 which is held from movement into the passage 20 of the tumbler by restricting the inner end of the bore, and the key 22 is provided in its respective side with a notch 28 adapted to partially receive the ball and hold it in a position wherein the plunger 27 is in turn held flush
- 15 with the inner end of the bore 23 of the block to thus permit rotation of the tumbler for consequent sliding movement of the bolt bar. Inasmuch as the bores of the tumbler and block are in alinement only
- 20 25 when the bolt bar 7 is in its limit of holding movement, the key cannot be withdrawn except in such position of the bar, and thus an incomplete operation of the device due to carelessness or otherwise is guarded against.
- 30 To facilitate positioning of the tumbler with its bore in proper alinement with the bore 23 of the block, the inner face edge of the bolt bar 7 is provided with a V-shaped notch 29, and a wire spring 30 has its ends secured to
- 35 the body plate 5 at the sides of the notch, when the bar is in its holding limit of movement, and the spring is intermediately provided with a series of coils 31, resiliently urged into the notch, the resilient pressure
- 40 45 of these coils being such that the tumbler through its gear engagement with the bar is held in said desired position.
- That end of the bolt bar channel toward which the bar is moved in its holding position
- 45 50 is closed by a plug 33 and this plug serves also to materially strengthen the adjacent plate portions forming the channel. The other end of the channel is normally open. Means, however, are provided for closing
- 55 60 this end of the channel end and for locking the bolt bar 7 in holding position, to thus prevent releasing manipulation thereof even through the medium of the key 22, this means comprising a staple member 33 adapted to be inserted in the end of the channel and provided in the outer side of one leg with a notch 34 adapted to be engaged by an inwardly struck tongue 35 preferably at the bend of the body plate to form the channel.
- 60 65 Thus the staple may be locked in a position locking the bolt bar and in a manner preventing possible tampering with a view to actuating the bolt bar to releasing position. Although in the present device I have shown a key controlled release means associated

with both binder heads, it is obvious that the said locking means may be associated with only one of the binder heads and that suitable conventional means may be provided for securing the flexible post members to the other binder head. 70

It is also obvious inasmuch as the essential feature of my present invention consists in providing a key controlled means for actuating the bolt bar wherein the turning of the key procures operative movement of the bar, that various embodiments of the invention other than the embodiment herein shown, may be employed without departing in any manner from the spirit of my invention. 75

I claim:

1. In a loose leaf binder, the combination of a binder head, one or a plurality of detachable binder posts, a bolt bar slidable in the channel to engage the posts to secure them to the head, spring means for urging the bar to its limit of engaging movement with respect to the post, and means closing one end of the said channel for locking the bolt bar in engaging position with respect 90 to the posts. 85

2. In a loose leaf binder the combination of a binder head, one or a plurality of detachable binder posts, a bolt-bar slidably carried by the head for engaging said posts to secure them to the head, a tumbler block carried by the head, a tumbler rotatable in said block, and operatively connected with the bolt bar for moving it, the tumbler and block being provided with bores adapted to aline, a plunger mounted in the bore of the block and extensible into the bore of the tumbler, a key member insertible in the tumbler for retracting the plunger from the bore thereof and for rotating the tumbler, and means resiliently urging the tumbler to a position wherein its bore alines with the bore of the block. 100 105

3. In a loose leaf binder the combination of a binder head, one or a plurality of detachable binder posts, a bolt-bar slidably carried by the head for engaging said posts to secure them to the head, a tumbler block carried by the head, a tumbler rotatable in said block, and operatively connected with the bolt bar for moving it, the tumbler and block being provided with bores adapted to aline, a plunger mounted in the bore of the block and extensible into the bore of the tumbler, a key member insertible in the tumbler for retracting the plunger from the bore thereof and for rotating the tumbler, and a spring engaging the bolt-bar for urging it to a position wherein the tumbler is positioned with its bore in alinement with 115 the bore of the block. 120

4. In a loose leaf binder, the combination of a binder head, one or a plurality of detachable binder posts, a bolt-bar slidably carried by the head for engaging said posts 130

to secure them to the head, a tumbler block carried by the head, a tumbler rotatable in said block, and operatively connected with the bolt-bar for moving it, the tumbler and block being provided with bores adapted to aline, a plunger mounted in the bore of the block and extensible into the bore of the tumbler, a key member insertible in the tumbler for retracting the plunger from the bore thereof and for rotating the tumbler, the bolt being provided with a V-shaped notch and a spring secured to the binder head and having a portion bearing against the bar and engageable in said V-shaped notch to procure alinement of the bores of the block and tumbler.

5. In a loose leaf binder the combination of a binder head, one or a plurality of detachable binder posts, a bolt-bar slidably carried by the head for engaging said posts to secure them to the head, a tumbler block carried by the head, a tumbler rotatably mounted in said block, and operatively connected with the bolt-bar for moving it, the tumbler and block being provided with bores adapted to aline, a plunger in the bore of the block, spring urged for engagement in the bore of the tumbler, a ball in the bore of the tumbler and a key member insertible in the tumbler and provided with a notch adapted to receive the ball whereby the ball may be held in a position holding the adjacent end of the plunger flush with the periphery of the tumbler to permit rotation of the tumbler by the key.

6. In a loose leaf binder the combination of a binder head provided with a channel,

one or a plurality of binder posts, a bolt bar slidable in the channel and adapted to engage said posts for securing them to the head, a permanent locking member insertible in the channel for holding the bar in engaging position with respect to the posts, said member being provided with a recess and a tongue struck inwardly from the channel to engage in said recess.

7. A binder head comprising a flat plate having one side portion bent laterally and inwardly to form an open channel, a block secured to the inner face of the plate, a gear wheel having its hub portion journaled in the block, a bolt bar slidable in the channel, teeth on the bolt bar meshing with the gear wheel and the hub of said gear wheel being provided with a key receiving opening.

8. In a loose leaf binder, the combination of a binder head, one or a plurality of binder posts, a bolt bar carried by the head and movable to engage said posts for securing them to the head, key controlled means for procuring operative movement of the bar, and means for closing one end of the binder head and operative independently of said key controlled means for locking the bolt bar in engaging position with respect to the posts, substantially as described.

In testimony that I claim the foregoing I have hereunto set my hand at Milwaukee, 70 in the county of Milwaukee and State of Wisconsin.

HENRY C. MILLER.
